UNITED STATES PATENT OFFICE.

DAVID P. T. DOUGLASS, OF JACKSON, TENNESSEE.

FLOOR-SCRAPER.

1,107,919.

Specification of Letters Patent. Patented Aug. 18, 1914.

Application filed March 28, 1913. Serial No. 757,399.

To all whom it may concern:

Be it known that I, DAVID P. T. DOUGLASS, a citizen of the United States, residing at Jackson, in the county of Madison and State of Tennessee, have invented new and useful Improvements in Floor-Scrapers, of which the following is a specification.

This invention relates to floor scrapers, and it has for its object to produce a tool of this class which shall be simple in construction and thoroughly efficient in operation.

A further object of the invention is to produce a simple and efficient tool which may be used in connection with scraper blades of different sizes and of different thickness, means being provided whereby such blades may be held securely in position for efficient operation.

A further object of the invention is to produce a device of the character described which may be readily tilted or adjusted to vary the angle of the blade with respect to the floor that is to be operated on so as to produce the best results according to the character of the blade, as well as the kind and quality of wood of which the floor that is to be scraped is constructed.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a side elevation of a floor scraper constructed in accordance with the invention. Fig. 2 is a rear elevation of the same. Fig. 3 is a top plan view. Fig. 4 is a longitudinal vertical sectional view taken on the line 4—4 in Fig. 3. Fig. 5 is a transverse sectional view taken on the line 5—5 in Fig. 3.

Corresponding parts in the several figures are denoted by like characters of reference.

The body of the improved tool consists of a rectangular block 10 of cast iron or other suitable heavy material, said block being

mounted for operation on a carriage C which includes an inclined platform 11 on which the body member 10 is secured by means of a bolt 12 for the passage of which two or more apertures 13 are provided in the said body member, the platform 11 being also provided with a slot 14 in order to enable the body member to be adjusted relatively to the carriage. The latter includes supporting wheels 15 preferably equipped with rubber tires 16, said wheels being set within the side edges of the body member 10. The carriage is also equipped with a lug 17 on which a handle 18 is pivotally mounted by means of a bolt 19, said lug being provided with an arcuate slot 20 concentric with the axis of the bolt 18 for the passage of an adjusting bolt 21, whereby the handle 18 may be secured at various angles with respect to the carriage.

The body member 10 which occupies, when mounted, an inclined position, as clearly seen in Figs. 1 and 4, is provided at its lower end with a stationary jaw 22 and a movable jaw 23, the latter being mounted on a pintle 24. Said stationary jaw has a terminal edge 25 which when the implement is in operation occupies a position which is substantially horizontal and parallel to the surface that is to be scraped. The jaw 23 overhangs the jaw 22 forming a lip 26, and the meeting faces 27, 28 of the two jaws are in substantially parallel relation to one another, said meeting faces or opposed faces being also provided with recesses 29, whereby the area of said meeting faces that contacts with the interposed blade 30 is materially reduced. Transverse bolts 31 are provided whereby the movable jaw may be secured firmly with respect to the fixed jaw so as to clamp the blade 30 securely between the opposed faces of the jaws.

For various kinds of work, mainly determined by the nature of the surface that is to be operated upon, whether the said surface be constructed of hard or of soft wood, blades 30 of varying thickness will be used.

The body member 10 is provided with lugs 32 between which the movable jaw member 23 is inset, said jaw member being provided with an aperture 33 of oval or oblong cross section for the passage of the pintle 24, which latter extends through the lugs 32, as shown. The jaw member 23 is provided with set screws 34 bearing against the pintle, and capable of being secured in adjusted

position by means of jam nuts 35. It will be seen that by adjustment of the set screws 34, the movable jaw may be so adjusted that the entire areas of the opposed faces of the fixed 5 and the movable jaws will contact with the blade 30, no matter what may be the thickness of said blade, thus enabling a blade of any desired thickness to be held between the jaws with absolute security and freedom 10 from vibration and hence in the best manner for efficient work. Coiled springs 36 seated in recesses 37 are provided for the purpose of forcing the movable jaw outward from the body member 10 when the set screws 34 15 are loosened. The jam nuts 35, as well as the heads of the bolts 12 and 31, are preferably provided with recesses to enable adjustment to be made by the use of a spanner or by means of some other tool, such as an ordinary punch whenever a wrench is not readily available.

From the foregoing description, taken in connection with the drawings hereto annexed, the operation and advantages of this 25 invention will be readily understood by those familiar with this class of devices. The scraper blade 30 when inserted between the opposed faces of the jaws is adjusted to project slightly beyond the overhanging lip 26 of the movable jaw which serves to steady the blade when the tool is drawn over the floor. The terminal face of the stationary jaw will be raised sufficiently above the floor 30 to permit of the passage of the chip or shaving.

With the improved tool a floor may be scraped as close to the mop boards as desired, the construction being such that the edge of the blade may be presented in con-

tact with the mop board. Corners and 40 angles may be scraped with equal facility, as well as the middle and exposed portion of the floor. Blades of different dimensions may be used and may be readily interchanged, as desired, and by the use of the 45 improved implement a great saving of labor may be effected, while the work may be performed even by labor that is not specially skilled in a superior workman-like manner.

Having thus described the invention, what 50 is claimed as new, is:

1. In a floor scraper, a body member having an integral stationary jaw and lugs adjacent thereto, a pivot member extending through the lugs, a movable jaw inset between the lugs and mounted on the pivot member, and clamping means for securing the movable jaw with respect to the stationary jaw; the movable jaw being provided with an elongated slot for the passage of the 60 pivot member and with set screws engaging said pivot member; and springs interposed between the jaws to force them apart.

2. In a device of the class described, a body member having a stationary jaw provided with lugs, a pintle fixed in said lugs, a movable jaw inset between the lugs and having an elongated aperture movably engaging the pintle, set screws engaging the 65 pintle through the movable jaw, and bolts 70 whereby the movable jaw is secured in fixed relation to the stationary jaw.

In testimony whereof I affix my signature in presence of two witnesses.

DAVID P. T. DOUGLASS.
